FLUID-OPERATED PUMP WITH SPACED MOTOR AND PUMP SECTIONS

Clarence J. Coberly, San Marino, Calif., assignor to Kobe, Inc., Huntington Park, Calif., a corporation of California

Filed Sept. 16, 1955, Ser. No. 534,712

6 Claims. (Cl. 103—46)

This invention relates to a fluid-operated pumping system which is of particular utility in pumping oil wells and which will be considered in connection with oil well pumping herein as a matter of convenience.

A fluid-operated pumping system for an oil well conventionally includes at least two tubings set in the well and connected at their lower ends to a fluid-operated pump having coupled motor and pump sections, the motor section of the pump being actuatable by an operating fluid, preferably oil, under pressure to actuate the pump section of the pump. The operating fluid under pressure is delivered to the motor section through one of the tubings mentioned, which tubing is referred to hereinafter as the power tubing. The spent operating fluid discharged by the motor section of the pump and the well fluid discharged by the pump section thereof may be conveyed to the surface separately through separate tubings, or may be mixed and conveyed to the surface through a common tubing. For convenience, the latter alternative will be considered herein, the common tubing for the spent operating fluid and well fluid discharged by the pump being referred to hereinafter as the production tubing.

In such a system, the fluid-operated pump may be either the "set" type, in which case it is rigidly connected to the lower ends of the power and production tubings, or the "free" type, in which case it is movable through one of the tubings, e.g., the power tubing, between the surface and an operating position adjacent the lower end of such tubing, the invention being disclosed as embodied in a free pump as a matter of convenience. Such free pump systems are well known in the art, one being described in detail in my Patent No. 2,338,903, granted January 11, 1944, to which reference is hereby made.

In such a conventional fluid-operated pumping system, the power and production tubings are desirably arranged in parallel, i.e., side by side, such an arrangement having several well-known advantages. Consequently, the two tubings occupy considerable lateral space in the well casing. In oil wells of substantial depth, it is common practice to reduce the diameter of the casing as the depth of the well increases, and it is also common practice to install perforated pipe in the producing zone of the well to exclude sand from the well. The perforated pipe is commonly set as a liner and is, of necessity, of smaller diameter than the casing thereabove. Under such conditions, it is not uncommon for the liner or casing in the production zone of the well to be so small to accommodate parallel power and production tubings and a primary object of the invention is to provide a fluid-operated pumping system which obviates this difficulty without sacrificing the parallel tubing arrangement.

More specifically, a primary object of the invention is to provide a fluid-operated pumping system wherein the motor and pump sections are spaced apart a substantial distance, with the motor section located in the casing above the producing zone of the well, where the

2

space available is of relatively large diameter, and with the pump section located beneath the motor section in the liner in producing zone of the well, where the space available is of reduced diameter. This permits the use of power and production tubings in parallel down to the point of reduced diameter and permits a single tubing for the pump section to be used in the producing zone, which is an important object of the invention.

A further object is to provide a pumping system in 10 incorporating a free pump of the foregoing character wherein in the tubing through which the pump is movable extends downwardly into the producing zone of the well to permit disposing the pump section of the pump therein, the other tubing terminating at a point a convenient distance above the liner. A related object in connection with a pumping system of this nature wherein the pump is movable through the power tubing, in which case the power tubing is longer than the production tubing, is to 15 discharge the well fluid pumped by the pump section into the lower end of the power tubing and to subsequently divert it into the production tubing at a point below the motor section of the pump. Another object in this connection is to provide packer means carried by the motor section of the pump and engageable with the power tubing for separating the well fluid discharged by the pump section from the operating fluid in the power tubing.

Another object is to provide a free pump wherein the motor and pump sections respectively include motor and pump pistons and are structurally disconnected except for 20 a rod means of substantial length which connects the pump piston to the motor piston.

An important object is to provide such a free pump wherein the rod means is flexible so that it may be wound on a reel, for example, as the pump section of the pump 25 is removed from the well.

Another object is to provide means for securing or supporting such a free pump in its operating position in the tubing in which it is disposed. Preferably, such securing or supporting means includes a hydraulically-actuated latch mechanism such as that disclosed and claimed 30 in my Patent No. 2,676,546, reference to which is hereby made.

I prefer to attain the foregoing objects and advantages of my invention, together with various other objects and 40 advantages thereof which will become apparent, through the employment of the exemplary embodiments which are illustrated in the accompanying drawings, and which are described in detail hereinafter. Referring to the drawings:

50 Fig. 1 is a diagrammatic utility view which shows the invention installed in a well;

Fig. 2 is a vertical sectional view of the upper portion of the invention;

70 Figs. 15, 16 and 17 are transverse sectional views respectively taken along the broken lines 15—15, 16—16 and 17—17 of Fig. 13; and,

Fig. 18 is a transverse sectional view taken along the broken line 18—18 of Fig. 14.

Referring particularly to Fig. 1 of the drawings, I show a fluid-operated pumping system which embodies the invention, the pumping system being installed in a well having an upper section of relatively large diameter which is encompassed by a main casing 21 and having a lower section of relatively small diameter which is encompassed by a perforated liner 22. The liner projects upwardly into the main casing and is provided at its upper end with a collar 23 which is adapted to be engaged by a conventional J-tool which is used on the lower end of a drill pipe (not shown) for setting the liner in place, as is well known in the art. The liner 22 extends downwardly into the oil-producing formation of the well and may be several hundred feet in length.

Suspended from a casing head 24 at the upper end of the main casing 21 are parallel power and production tubings 25 and 26, the production tubing terminating above the liner 22 at a point adjacent the lower end of the main casing 21 and being connected to the power tubing by a fitting 27. The power tubing 25 is of substantially greater length than the production tubing 26 and includes a lower section 28 which extends downwardly from the fitting 27 into the liner 22. As will be discussed in more detail hereinafter, a fluid-operated pump 30 of the invention, shown in Figs. 2 to 10, is movable downwardly through the power tubing 25 into an operating position adjacent the lower end thereof, the pump including a motor section 31 (Figs. 2 to 5) which is disposed in the power tubing above the lower end of the fitting 27 when the pump is in its operating position, and including a pump section 32 (Figs. 5 to 8) which is disposed in the lower section 28 of the power tubing below the fitting 27 when the pump is in its operating position.

The power and production tubings 25 and 26 are connected at their upper ends to a selector valve 33 which is operable by a handle 34, a supply pipe 35 and a discharge pipe 36 also being connected to the selector valve. The supply pipe is connected to a source of operating fluid under pressure, which may be a conventional triplex pump 37. The discharge pipe 36 leads to a suitable point of disposal for the fluid discharge by the fluid-operated pump 30. In one position of the handle 34, the selector valve 33 connects the supply pipe 35 to the power tubing 25 and connects the discharge pipe 36 to the production tubing 26 so that operating fluid under pressure flows downwardly through the power tubing to the motor section 31 of the pump 30 and so that fluid discharged by the pump 30 flows upwardly through the production tubing into the discharge pipe. In another position of the handle 34, the selector valve 33 connects the production tubing 26 to the supply pipe 35 and connects the power tubing 25 to the discharge pipe 36 to remove the fluid-operated pump 30 from the well hydraulically. All of this will be discussed in more detail hereinafter.

As best shown in Fig. 3, the power tubing 25 includes an upper section 41 which is threaded at its lower end into the upper end of a sealing collar 42, the latter being provided with an internal annular shoulder 43 which serves as a seat for a cylindrical sleeve 44. The upper end of this sleeve provides an upper annular seating shoulder 45. Formed in the sealing collar 42 below the shoulder 43 is an annular recess 46 which provides a lower annular seating shoulder 47.

As best shown in Fig. 4, the power tubing 25 includes an intermediate section 50 which is threaded at its upper end into the lower end of the sealing collar 42 and which, as best shown in Fig. 5, is threaded at its lower end into the upper end of a bore 51 through the fitting 27. Located beside the bore 51 in the fitting 27 is a bore 52 into which the lower end of the production tubing 26 is threaded, the bores 51 and 52 being connected

in fluid communication by a port 53 in the fitting. The lower section 28 of the power tubing 25 is threaded at its upper end into the lower end of the bore 51 through the fitting 27 and extends downwardly from this fitting into the liner 22.

As best shown in Figs. 7 and 8, the lower end of the lower section 28 of the power tubing is threaded into a coupling 55 which, in turn, is threaded into a tubular inlet element 56, the latter being open at its lower end to communicate with the well. The inlet element 56 is provided with an internal annular shoulder 57 on which is seated a collar 58, the latter being provided with an annular seating face 59. Seated on the face 59 is a standing valve assembly 60 which is provided with a bore 61 therethrough and which is provided with a ball check valve 62 at the lower end of such bore, the ball check valve being adapted to move upwardly to admit well fluid from the liner 22 into the standing valve assembly, but being adapted to seat to prevent reverse flow. The standing valve assembly 60 is provided at its upper end with a tapered pump seat 63 for the fluid-operated pump 30 of the invention, which will now be considered in detail.

Referring particularly to Figs. 4 and 5, the motor section 31 of the fluid-operated pump 30 is disposed in the power tubing 25 above the port 53 in the fitting 27 when the pump is in its operating position. Any suitable fluid-operated motor may be employed for the motor section 31 of the pump 30 so that it will not be described in detail herein. Briefly, the motor section 31 includes a motor cylinder 66 having a motor piston 67 reciprocable therein, a piston rod 68 being connected to the lower end of the motor piston and extending through the lower end of the motor cylinder, and a valve rod 69 being connected to the upper end of the motor piston and extending through the upper end of the motor cylinder. As is well known in the art, the valve rod 69 cooperates with a motor valve (not shown) which applies an alternating fluid pressure differential to the motor piston 67 to reciprocate it in the motor cylinder.

As best shown in Figs. 2 and 3, connected to the upper end of the motor cylinder 66 is a tubular fitting 72 having a tubular packer mandrel 73 threaded into its upper end. Threaded onto the upper end of the packer mandrel 73 is a member 74 having a frustoconical nose 75 which is adapted to be engaged by a pump catcher (not shown) incorporated in the body of the selector valve 33 when the pump 30 is removed from the well, as will be discussed in more detail hereinafter. The valve rod 69 is of smaller external diameter than the internal diameters of the packer mandrel 73 and the tubular fitting 72 to provide therebetween an annular space 76 which serves as an operating fluid intake for the motor section 31 of the pump 30, the operating fluid intake communicating with the interior 45 of the power tubing 25 through ports 77 in the member 55 at the upper end of a packer mandrel. As is conventional with free pumps, the packer mandrel 73 carries packers 78 which provide a fluid-tight seal relative to the power tubing 25 whenever the pressure below such packers exceeds the pressure thereabove, as is the case during removal of the pump 30 from the well, which will be discussed in more detail hereinafter.

The tubular fitting 72 carries packer means 81 which makes a fluid-tight seal with the sleeve 44 in the sealing collar 42 when the fluid-operated pump 30 is in its operating position so as to isolate the sections of the power tubing below the sealing collar from those thereabove. The packer means 81 comprises a sealing ring 82, preferably an O-ring, which engages the sleeve 44 when the fluid-operated pump is in its operating position and which is disposed in an annular groove 83 formed between two annular elements 84 and 85. The annular elements 84 and 85 encircle the tubular fitting 72 with the element 84 seated against an external shoulder 86 on this fitting,

a fluid-tight seal between the element 84 and the fitting 72 being provided by a sealing ring 87. Seated on the annular element 85 is a sleeve 90 which encircles the upper end of the tubular fitting 72 and which is clamped between the annular element 85 and a washer 91 by a nut 92 threaded on the lower end of the packer mandrel 73. The sleeve 90 is provided at its upper end with a downwardly facing shoulder 93 which seats on the seating shoulder 45 at the upper end of the sleeve 44 when the fluid-operated pump is in its operating position.

As best shown in Figs. 3 and 9, the lower end of the tubular fitting 72 is enlarged and is provided with a plurality of circumferentially spaced, vertical bores 95 for vertically movable pins 96, the latter being biased downwardly by compression springs 97 which are seated against the upper ends of the pins and against the lower face of the annular element 84. The lower ends of the pins 96 engage radially movable latch elements 98 which, as best shown in Figs. 3 and 10, are slideable in circular openings 99 formed in the tubular fitting 72. Each of the latch elements 98 is provided with packing 100 which entirely encircles it to provide a fluid-tight seal. Each of the latch elements is provided with a lower seating face 101 which is adapted to rest on the lower seating shoulder 47 of the sealing collar 42, and each of the latch elements is provided in its upper surface with a groove 102 in which the corresponding pin 96 is disposed, the pins serving as stops to limit inward and outward radial movement of the latch elements. It will be noted that the inner ends of the latch elements 98 are exposed to the annular operating fluid intake 76 and that the outer ends thereof are exposed to the fluid pressure obtaining in an annular space 105 between the sealing collar 42 and the tubular fitting 72. As shown in Figs. 4 and 5, the annular space 105 extends downwardly between the motor cylinder 66 and the intermediate section 50 of the power tubing 25, and communicates at its lower end with the port 53 in the fitting 27.

Referring particularly to Figs. 6 and 7, the pump section 32 of the fluid-operated pump 30 is preferably of the single-acting type and includes a pump cylinder 108 having a pump piston 109 reciprocable therein. A piston rod 110 is connected to the upper end of the pump piston 109 and extends through the upper end of the pump cylinder 108.

It will be noted that there is no structural connection between the pump cylinder 108 and the motor cylinder 66, the only connection between the motor and pump sections 31 and 32 of the fluid-operated pump 30 being a flexible rod means 111 which is connected at its upper end to the piston rod 68 attached to the motor piston 67 and which is connected at its lower end to the piston rod 110 attached to the pump piston 109. The flexible rod means 111 is illustrated as a woven wire cable 112 having fittings 113 and 114 swaged onto its upper and lower ends, respectively. The fitting 113 is threaded onto the lower end of the piston rod 68 and the fitting 114 is threaded onto a similar fitting 116 which is threaded onto the piston rod 110.

In practice, the pump section 32 of the fluid-operated pump 30 may be disposed a substantial distance below the motor section 31 thereof, the distance between the motor and pump sections being, for example, several hundred feet or more. Under such conditions, the wire cable 112 may be of very substantial length and is responsible for a substantial portion of the over-all length of the pump 30.

Referring to Figs. 6 and 7 and going from the upper end of the pump section 32 toward the lower end thereof, the pump cylinder 108 is closed at its upper end by an element 120 which serves as a guide for the piston rod 110 and which is provided with discharge ports 121 therein for fluid discharged by the pump section, such

discharge ports communicating with the lower section 28 of the power tubing 25. Only one of the discharge ports 121 is visible in the drawings. Connected to the lower end of the element 120 is a cup-shaped element 122 having a transverse wall 123 through which the piston rod 110 extends and which serves as an additional guide for the piston rod, the wall 123 being provided with ports 124 therethrough which lead to the discharge ports 121. Connected to the lower end of the element 122 is a sleeve 125 which is connected to a pump barrel 126 by a coupling 127, the pump barrel, as best shown in Fig. 7, having a liner 128 which defines the pump cylinder 108, pressed thereto. The pump piston 109 makes a fluid-tight, sliding fit with the liner 128. A coupling 129 connects the lower end of the pump barrel 126 to a sleeve 130 which is connected at its lower end to an inlet valve assembly 131, the latter providing fluid communication between the interior of the pump cylinder 108 and the standing valve assembly 60 so that fluid from the well 20 may flow through the standing valve assembly and through the inlet valve assembly 131 into the lower end of the pump cylinder. The inlet valve assembly 131 includes a ball check valve 132 which permits upward flow of well fluid into the pump cylinder 108, but which prevents reverse flow. The inlet valve assembly 131 includes an element 133 which is tapered at its lower end to seat on the tapered pump seat 63. The element 133 also carries a latch means 134 comprising fingers 135 having outwardly and downwardly sloping external shoulders 136 which are adapted to engage a downwardly facing shoulder 137 formed on the inner surface of the coupling 55. The fingers 135 are connected at their upper ends by a ring 138 which is seated on an external shoulder 139 on the element 133 to support the latch means 134. As will be apparent, the latch means 134 provides a means for releasably securing the pump cylinder 108 relative to the power tubing 25, the sloping shoulders 136 on the fingers 135 being adapted to disengage the shoulder 137 to release the pump cylinder 40 in response to a predetermined upward force applied thereto.

As shown in Fig. 7, the pump piston 109 is generally tubular and includes a sleeve 147 which is connected at its upper end to a fitting 148 having a bore 149 therethrough and having lateral discharge ports 150 which communicate with such bore, the piston rod 110 being threaded into the upper end of the bore 149. Connected to the lower end of the sleeve 147 is a working valve assembly 151 which includes a ball check valve 152 adapted to open upwardly to permit upward flow of fluid through the pump piston during the downward, or return, stroke thereof, but adapted to close during the upward, or pumping, stroke of the pump piston to prevent flow therethrough.

Considering the operation of the embodiment hereinbefore described, when the fluid-operated pump 30 is to be installed in the well, the pump section 32 thereof is inserted into the upper end of the power tubing 25, followed by the flexible rod means 111 and the motor section 31, the latch elements 98 being moved inwardly into their retracted positions prior to insertion of the motor section into the power tubing so that the pump 30 may pass downwardly through the power tubing. The upper end of the power tubing 25 is then closed in any suitable manner and the handle 34 of the selector valve 33 is moved to a position such that the power and production tubings 25 and 26 are connected to the supply and discharge pipes 35 and 36, respectively. Subsequent operation of the triplex pump 37 results in the delivery 60 of operating fluid under pressure to the upper end of the power tubing 25 through the supply pipe 35 and the selector valve 33 to move the fluid-operated pump 30 downwardly through the power tubing into its operating position, as shown in Figs. 2 to 8 of the drawings. Any fluid in the power tubing below the pump 30 is dis-

placed upwardly through the port 53 in the fitting 27 into the production tubing 26, from which it flows through the selector valve 33 into the discharge pipe 36. During the downward movement of the fluid-operated pump 30, the latch elements 98 are frictionally held in their retracted positions by the compression springs 97 acting through the pins 96. Since the fluid pressure required to move the pump 30 downwardly through the power tubing is relatively small, the latch elements 98 are not moved outwardly thereby.

As the fluid-operated pump 30 reaches its operating position, the element 133 at the lower end of the pump section 32 engages the pump seat 63 and the latch means 134 releasably secures the pump section in place. At substantially the same time, the shoulder 93 upon the sleeve 90 engages the shoulder 45 at the upper end of the sleeve 44 to prevent downward movement of the motor section 31 of the pump beyond its operating position. By this time, the packer means 81 engages the sleeve 44 to prevent downward flow of the operating fluid past the motor section. Consequently, the operating fluid pressure above the motor section 31 increases, such increased operating fluid pressure being applied to the inner ends of the latch element 98 through the operating fluid intake 76 and the ports 77 in the member 74. As the operating fluid pressure builds up to its normal value, the latch elements 98 are forced outwardly into the positions shown in Fig. 3 in which the lower seating faces 101 thereof engage the lower seating shoulder 47 to support the motor section 31 of the pump 30. As will be noted, the area of engagement between the shoulder 93 and the upper seating shoulder 45 is relatively small due to space requirement and would not support the full pressure of the operating fluid, which might provide a pressure differential across the packer means 81 of 2,500 pounds per square inch or more. Consequently, this engagement is not designed to do more than check the downward movement of the fluid-operated pump 30 and temporarily support the pump in its operating position. As soon as the downward pressure of the operating fluid starts to rise, the latch elements 98 are moved outwardly as described to support the motor section 31 of the pump and to withstand any downward fluid pressure differential thereon.

With the fluid-operated pump 30 thus installed in the well, the operating fluid flows downwardly through the operating fluid intake 76 to operate the motor section 31, thereby reciprocating the motor piston 67 in its cylinder 66. Such reciprocatory movement of the motor piston 67 is communicated to the pump piston 109, the required to produce the upward stroke of the pump piston being communicated thereto by the flexible rod means 111 and the force required to produce the downward stroke of the pump piston being provided by gravity. During the upward stroke of the pump piston 109, the working valve assembly 151 carried thereby is closed so that fluid is discharged from the pump cylinder 108 through the discharge ports 121. At the same time, the inlet valve assembly 131 and the standing valve assembly 60 open so that well fluid is drawn into the lower end of the pump cylinder 108. The fluid discharged from the pump cylinder flows upwardly through the lower section 28 of the power tubing 25 and through the port 53 in the fitting 27 into the production tubing 26, the packer means 81 serving to separate the operating fluid in the power tubing above the motor section 31 from the production flow. The production fluid flows from the production tubing 26 through the selector valve 33 into the discharge pipe 36. It will be noted that the annular space 105 communicates the production fluid pressure to the outer ends of the latch elements 98 because of the location of the latch elements below the packer means 81, thereby providing a fluid-pressure differential across the latch elements which retains them in their extended positions to support the motor section of

the pump. During the upward stroke of the pump piston 109, the pump cylinder 108 is retained in its operating position by its own weight and by the latch means 134.

During the downward stroke of the pump piston 109, the working valve assembly 151 carried thereby opens to permit displacement of well fluid from the lower end of the pump cylinder into the upper end thereof. At the same time, the inlet valve assembly 131 closes to prevent discharge of fluid back into the well.

When removal of the fluid-operated pump 30 from the well is desired for any reason, the handle 34 of the selector valve 33 is moved to a position such that the selector valve connects the supply pipe 35 to the production tubing 26 and connects the power tubing 25 to the discharge pipe 36. The operating fluid under pressure then flows from the triplex pump 37 downwardly through the production tubing 26 and enters the power tubing 25 below the motor section 31 through the port 53 in the fitting 27. As such fluid pressure builds up, it acts on the outer ends of the latch elements 98, through the annular space 105, to retract the latch elements. Subsequently, as the operating fluid pressure continues to build up, it acts on the lower end of the motor section 31 to start it upwardly through the power tubing 25. Such upward movement of the motor section 31 is communicated to the pump section 32 through the flexible rod means 111, the latch means 134 releasing the pump section automatically after a predetermined pressure has built up below the motor section 31. The external diameter of the pump section 32 is such that a clearance is provided between the pump section and the walls of the power tubing 25 so that the pump section is substantially hydraulically balanced after it has been unseated.

As the fluid operated pump 30 moves upwardly in the power tubing 25, the packer means 81 disengages the sleeve 44. Thereafter, the operating fluid pressure is applied to the packers 78 on the packer mandrel 73 to move the pump 30 upwardly through the power tubing to the surface. Since the motor section 31 of the pump 30 and the cable 111 are relatively light, only a relatively small fluid pressure below the packers 78 is required to move the pump upwardly to the surface, a pressure of 80 pounds per square inch, for example, being sufficient. Consequently, there is substantially no tendency for the packers 78 to blow out during upward movement of the pump. It will be noted that as soon as the pump section 32 unseats from the pump seat 63, the standing valve assembly 60 closes to prevent discharge of the operating fluid into the well.

When the pump 30 reaches the surface, the motor section 31 thereof is removed from the power tubing 25 and the flexible rod means 111 may be wound on a drum or reel, for example, which is an important feature of the invention. Subsequently, the pump section 32 may be removed from the power tubing.

In the alternative embodiment illustrated in Figs. 11 to 18 of the drawings, power and production tubings 225 and 226 respectively corresponding to the power and production tubings 25 and 26 are employed. As shown in Fig. 13, the tubings 225 and 226 are connected by a fitting 227 from which depends a lower section 228 of the power tubing 225 corresponding to the lower section 28 of the power tubing 25. The embodiment presently under consideration includes a fluid-operated pump 230 which includes a motor section 231 similar to the motor section 31. The pump 230 also includes a pump section which is identical to the pump section 32 and which is therefore not illustrated.

The fitting 227 is essentially a combination of the fitting 27 and the sealing collar 42, the fitting 227, as shown in Fig. 13, being provided with a bore 251 therethrough into the upper end of which an upper section 241 of the power tubing 225 is threaded and into the lower end of which the lower section 228 thereof is threaded. The lower end of the production tubing 226

is threaded into a bore 252 in the fitting 227, the bores 251 and 252 communicating below the motor section 231 through a port 253. Disposed in the bore 251 is a cylindrical sleeve 244 corresponding to the sleeve 44 and formed in the bore 251 is an annular recess 246 corresponding to the annular recess 46, the annular recess 246 providing an annular seating shoulder 247. The motor section 231 comprises a motor cylinder 266 having a motor piston 267 reciprocable therein, a tubular piston rod 268 being connected to the lower end of the motor piston and extending through the lower end of the motor cylinder. Connected to the upper end of the motor cylinder 266 is a solid packer mandrel 273 which carries a member 274 having a nose 275 adapted to be engaged by a pump catcher (not shown). The packer mandrel 273 carries at least one packer 278 corresponding to the packer 78.

Referring particularly to Fig. 13, at the lower end of the motor cylinder 266 is a tubular fitting 272 which corresponds to the tubular fitting 72. The tubular fitting 272 is provided with a plurality of ports, best shown in Figs. 13 and 15, which serve as an operating fluid intake 276 for the motor section 231 of the fluid-operated pump 230. The operating fluid intake 276 communicates with the lower end of an annular space 277 between the power tubing 225 and the motor cylinder 266 so that operating fluid may reach the intake 276 by way of such annular space.

The tubular fitting 272 carries a packer means 281 for separating the lower section 228 of the power tubing 225 from the upper section 241 thereof, thereby separating the operating and production fluid. The packer means 281 comprises an O-ring 282 which is adapted to engage the sleeve 244 and which is disposed in a groove 283 in the tubular fitting 272.

Threadedly connected to the lower end of the tubular fitting 272 is another tubular fitting 294 having a plurality of circumferentially spaced, vertical bores 295 for pins 296 which are biased downwardly by compression springs 297 seated against the lower face of the fitting 272. The lower ends of the pins 296 engage latch elements 298 which correspond to the latch elements 98, the latch elements 298 being slidable radially in circular openings 299 formed in the tubular fitting 294. Packing 300 surrounds each latch element 298 to provide a fluid-tight seal. The latch elements 298 are provided with lower seating faces 301 which are adapted to engage the annular seating shoulder 247, the internal diameter of the annular shoulder 247 being sufficiently small that the latch elements 298 cannot move therapast when the latch elements are retracted during downward movement of the pump 230. Inward and outward movement of the latch elements 298 is limited by the pins 296 which are disposed in grooves 302 in the upper surfaces of the latch elements.

The latch elements 298 are moved outwardly into their extended positions by application of the operating fluid pressure to the inner ends thereof in the same manner as the latch elements 98, the operating fluid pressure being applied to the inner faces of the latch elements 298 in the following manner: The tubular piston rod 268 is provided with radial ports 303 therein, as best shown in Figs. 13 and 15, which communicate with a chamber 304 for any position of the motor piston 267, the chamber 304 continuously communicating with the operating fluid intake 276. Thus, the pressure in the tubular piston rod 268 is always the operating fluid pressure above the packer means 281. Below the radial ports 303 in the tubular piston rod are two sets of radial ports 305 and 306, the former being shown in Figs. 13 and 16 and the latter in Figs. 14 and 18. One or the other of the sets of ports 305 and 306 is always in communication with an annular space 307 between the tubular piston rod 268 and the tubular fitting 294, either directly or through an annular space 308 between the tubular

piston rod and a tube 309 which is threaded into the lower end of the fitting 294, the tube 309 being closed at its lower end to make a fluid-tight, sliding fit with the piston rod. The inner ends of the latch elements 298

5 are open to the annular space 307 so that the operating fluid pressure within the tubular piston rod is applied thereto through one or more of the sets of ports 305 and 306 and one or more of the annular spaces 307 and 308.

10 As best shown in Fig. 14, the tubular piston rod 268 is connected to a flexible rod means 311 in substantially the same manner as the piston rod 68 is connected to the flexible rod means 111.

The operation of the alternative embodiment illustrated 15 in Figs. 11 to 18 is similar to that of the embodiment illustrated in Figs. 1 to 10 and does not need to be discussed in detail. Briefly, during installation of the fluid-operated pump 230, the latch elements 298 are in their retracted positions to clear the inner walls of the power tubing 225 and the fitting 227. However, the retracted latch elements 298 engage a sufficient area of the annular seating shoulder 247 to check the downward movement of the motor section 231 when the pump 230 reaches its operating position. Subsequently, the operating fluid 25 pressure increases and is communicated to the inner ends of the latch elements 298 through the annular space 277, the operating fluid intake 276, the chamber 304, the radial ports 303, the tubular piston rod 268, the radial ports 305 (or the radial ports 306) and the annular space 307 (or the annular spaces 308 and 307). In all other respects, the operation of the pump 230 is substantially 30 identical to that of the pump 30.

As hereinbefore discussed, the present invention, by spacing the motor and pump sections of a fluid-operated 35 pump apart in the well, permits the use of parallel tubings, with their attendant advantages, in wells having bottom hole diameters which normally would not permit the use of parallel tubings. With the present invention, practical pumping depths with this type of equipment may 40 be substantially extended.

Although I have shown and described two preferred 45 embodiments of the invention, it will be understood that various changes, modifications and substitutions may be incorporated in either embodiment without departing from the spirit of the invention and, therefore, I do not intend to be limited to the specific construction shown and described, but desire to be afforded the full scope of the following claims.

I claim as my invention:

50 1. In a fluid-operated pumping system, the combination of: power and production tubings set in a well; a fluid-operated pump movable relative to said tubings through one of them into an operating position adjacent the lower end thereof, said pump including spaced motor and pump sections each of which includes a cylinder having a piston therein, and including rod means providing the sole connection between said motor and pump sections for connecting said pistons together, and said pump including elements engageable with elements of said

55 one tubing for supporting said motor and pump sections in spaced relation independently of each other, said motor section being provided with an intake and said pump section being provided with an inlet and an outlet; means for connecting said intake in fluid communication with said power tubing; means for connecting said inlet in fluid communication with the well; and means for connecting said outlet in fluid communication with said production tubing.

70 2. In a fluid-operated pumping system, the combination of: a pair of tubings set in a well; a fluid-operated pump movable relative to said tubings through one of them into an operating position adjacent the lower end thereof, said pump including spaced motor and pump sections each of which is provided with a cylinder having a piston 75 therein, and including rod means connecting said pistons

together and forming the sole connection between said sections; means providing a port connecting said tubings in fluid communication at a point between said motor and pump sections when said pump is in said operating position; packer means carried by said motor section and disposed above said port when said pump is in said operating position for providing a fluid-tight seal between said motor section and said one tubing; and means for securing said pump in said operating position.

3. In a fluid-operated pumping system, the combination of: a pair of tubings set in a well, one of said tubings being substantially longer than the other; means providing a port in fluid communication with the lower end of said other tubing and in fluid communication with said one tubing at a point a substantial distance above the lower end thereof; a fluid-operated pump movable relative to said tubings and through said one tubing into an operating position therein and including operatively connected motor and pump sections respectively disposed above and below said port when said pump is in said operating position, said motor section having an intake which communicates with said one tubing above said port when said pump is in said operating position, and said pump section having an inlet which communicates with the well and having an outlet which communicates with said one tubing below said port when said pump is in said operating position; packer means carried by said pump and engageable with said one tubing between said intake and said port when said pump is in said operating position for providing a fluid-tight seal between said intake and said port; and means for securing said pump relative to said one tubing.

4. A fluid-operated pumping system according to claim 3 wherein said motor and pump sections respectively include motor and pump cylinders respectively having therein motor and pump pistons and wherein said pump includes flexible, reelable rod means connecting said motor and pump pistons together and providing the sole connection between said motor and pump sections.

5. In combination in a well bore: a perforated liner in the well bore adjacent the bottom thereof, the inside diameter of said liner being less than the diameter of the well bore thereabove; a pair of tubings set in the well bore

and interconnected therein above said liner, one of said tubings being substantially longer than the other and extending downwardly into said liner; and a fluid-operated pump carried by said one tubing and including vertically spaced, operatively connected motor and pump sections respectively comprising motor and pump cylinders respectively having motor and pump pistons therein, said pump including a rod connecting said motor and pump pistons, said motor section being located entirely above said liner and said pump section being located entirely within said liner.

6. In a fluid-operated pump, the combination of: a motor section adapted to be disposed in a well and including a motor cylinder having a motor piston reciprocable therein, said motor section including motor valve means for applying an alternating fluid pressure force differential to said motor piston to reciprocate it in said motor cylinder; a pump section adapted to be disposed in the well below said motor section and including a pump cylinder having a pump piston therein; rod means connecting said pump piston to said motor piston; means connected to said motor cylinder for supporting said motor section in the well; and means connected to said pump cylinder for supporting said pump section in the well below and spaced from said motor section.
